[57] CLAIM

The ornamental design for an outsole of a shoe, as shown and described.

DESCRIPTION

FIG. 1 is a perspective view of the outsole of a shoe showing my new design;

FIG. 2 is a plan view of the outsole of a shoe shown in FIG. 1;

FIG. 3 is a first side view of the outsole of a shoe shown in FIG. 1;

FIG. 4 is a second side view of the outsole of a shoe shown in FIG. 1;

FIG. 5 is a front elevational view of the outsole of a shoe shown in FIG. 1; and,

FIG. 6 is a rear elevational view of the outsole of a shoe shown in FIG. 1.

The phantom lines showing of a shoe upper shown in FIGS. 1-6 are for illustrative purposes only and form no part of the claimed design.

1 Claim, 3 Drawing Sheets
